UNITED STATES PATENT OFFICE.

FRED RICKS, OF LEICESTER, ENGLAND, ASSIGNOR TO UNITED SHOE MACHINERY CORPORATION, OF PATERSON, NEW JERSEY, A CORPORATION OF NEW JERSEY.

SHOE STIFFENER AND METHOD OF MAKING IT.

Application filed October 18, 1923. Serial No. 669,429.

To all whom it may concern:

Be it known that I, FRED RICKS, a subject of the King of England, residing at Leicester, Leicestershire, England, having invented certain Improvements in Shoe-Stiffeners and Methods of Making Them, of which the following description, in connection with the accompanying drawings, is a specification, like reference characters 10 on the drawings indicating like parts in the several figures.

This invention relates to thermoplastic stiffeners for parts of boots and shoes and to a method of making them, and is here- 15 in set forth in connection with a toe stiffener. The term "thermoplastic" denotes that quality of a substance whereby it is hard and somewhat resilient at ordinary temperatures but may be rendered plastic 20 enough by heat to be molded. A toe stiffener of the thermoplastic type and the method of using it is disclosed, for example, in Patent No. 1,124,835.

Thermoplastic toe stiffeners, as heretofore 25 used, have commonly consisted of a blank of felt impregnated with a thermoplastic agent such, for example, as a mixture of 75% of colophony and 25% of blown asphalt. Such stiffeners are incorporated in 30 boots and shoes by inserting them in place in the boot or shoe, heating them to render them limp and plastic, and then molding them to the desired shape during the last- 35 ing operation.

In the manufacture of so-called "soft-toed shoes" or "plain vamp shoes" which have no toe cap or tip, it is particularly desirable to secure a gradual blending, in 40 point of resilience or pliability, between the stiffened toe portion and the upper adjacent to the toe portion so that no sharply defined ridge shall be visible in the finished shoe or become evident after the shoe has 45 been worn.

The present invention has particularly for its object to provide stiffeners of the said type which shall be well adapted for use in plain vamp shoes to stiffen the toe portions thereof without showing through the 50 upper leather an imprint of the stiffener along the rear edge of the latter. Difficulties have occurred in securing the desired conditions with stiffeners of the type in ques-

tion hitherto used since, unless the blank be given a very thin edge by a very wide scarf 55 along its rear edge, the stiffener is too rigid at its edge when it has set in the shoe; while, if the requisite wide scarf be given, the extreme margin of the skived blank is very weak and the stiffener is apt to tear 60 at that place when being lasted into a shoe. Moreover such stiffeners, while they must be firm and rigid, must nevertheless be of comparatively limited thickness and this is 65 a condition which renders difficult the production of a wide, small angle scarf.

According to the present invention there is provided a thermoplastic stiffener comprising two or more superposed layers of absorbent fabric which are charged with 70 thermoplastic substance and are securely united together to form a unitary structure, the stiffener having a relatively thin and flexible rear edge by reason of the projection of an unskived marginal portion of an 75 outer one of the layers beyond the rear margin of the adjacent sheet.

The said outer sheet will generally be of such nature and thinness as renders it unsuitable for skiving or for more than a very 80 slight shaving of one of its surfaces; and, while in many instances it may be allowed to retain its full thickness to the extreme rear edge of the stiffener, such thinning treatment as it may be given will in the main be 85 brought about by the application of heat and pressure.

Referring now to the accompanying drawings,

Figure 1 is a sectional elevation of one 90 form of stiffener at an intermediate stage in its manufacture;

Fig. 2 is a similar view of the same stiffener at a later stage;

Fig. 3 is a plan of the finished stiffener; 95

Fig. 4 is a plan of a second form of stiffener;

Fig. 5 is a sectional elevation of the stiffener of Fig. 4 at an intermediate stage in 100 its manufacture; and

Fig. 6 is a sectional elevation of this stiffener at a later stage.

It should here be pointed out that the outline of the stiffeners shown in Figs. 3 and 4 105 is purely by way of example as the outline will obviously be varied according to the

needs of particular shapes or styles of shoes. In particular the convex rear edge shown will in many cases be replaced by a deeply concaved rear edge for certain kinds of shoes.

In the stiffener shown in Figs. 1, 2 and 3 two layers or laminations 3 and 5 are used. Each is composed of strong woven cotton fabric. The fabric for the layer 5, which is to furnish the extreme margin of the rear portion of the stiffener is preferably of less substance than the other, the respective thicknesses being for example fifteen and thirty thousandths of an inch when measured in the unimpregnated but fluffed-up or napped condition which will be referred to hereinafter. The thinner of these is therefore so thin that it cannot readily be skived when it has been charged with the thermoplastic substance without being torn or shredded.

The thermoplastic stiffening agent with which both layers are impregnated is conveniently used as the bond between the layers, and the laminated impregnated material is conveniently produced in sheet form by leading the layers separately under separate guide rolls into a tank of the molten thermoplastic stiffening agent, the layers being thereafter led under a common guide roll while still immersed in the said agent so as to be superposed one upon the other in the mass of molten material. The compound sheet, as it leaves the tank, may pass between rollers which compact the layers together and give the sheet a uniform predetermined thickness before it sets.

After the sheet has cooled and becomes stiff, the stiffener blanks may be died out of it by the use of any suitable machine. Instead, however, of proceeding thereupon to skive the rear margin of the whole blank, as has heretofore been the common practice, the rear margin of the layer 3 is cut away partly or wholly, as may be desired, so as to leave the then projecting rear margin of the lower layer uncut, the thin edge of the lower layer then forming all or nearly all of the rear edge of the blank. In the illustrative stiffener the cutting has been so carried out that the ends 13 of the rear margin of the layer 3 have been left uncut, while the portion intermediate the ends has been cut away. The purpose of this is to provide thick, stout portions at the locality of the ends 13 so that at those portions of the stiffener which are to be grasped by the side pincers of the pulling-over machine or to be acted upon by the wipers of the lasting machine when the stiffener is hot and limp, there shall be adequate substance and strength to prevent rupture or undue distortion of the stiffener.

This cutting operation may conveniently be performed by a machine of the well-

known type which has matrix and presser rollers and fixed knife, the matrix being specially formed with a properly shaped step so as to cause the knife to cut through the layer 3 at a distance (for example one quarter of an inch) from its rear edge and then to pass between the layers 3 and 5 from the locality of entry of the knife into the layer 3 to the extreme rear edge of the stiffener, thereby splitting the layers apart and removing the severed portion of the layer 3. In producing the stiffener shown in the drawings the step in the matrix roll was so formed as to cause the knife to leave the end portions 13 of the rear margin of the layer 3 uncut for the purpose described above. And, if desired, the matrix may be so shaped as to cause the knife to produce a slight bevel as at 9 where its cut starts, such beveling tending to facilitate the subsequent obliteration of the shoulder 11 which is formed by the cut at this locality, which obliteration is one of the results of the next step in the manufacture of the stiffener.

The blank is now subjected to pressure by a hot iron along the edge 7 of the layer 5, along the shoulder 11 and over the face 15 of the layer 5, which has become exposed by the removal of the rear marginal portion of the layer 3. The purpose of ironing the edge 7 is to thin it somewhat as indicated at 21. The purpose of ironing the shoulder 11 is first to fuse the layers 3 and 5 together along the line of cut where they may have become slightly parted during the cutting operation, second to increase the extent and change the angle of the bevel 9 until this bevel has the extent and inclination indicated at 17 in Fig. 2, and third to cause some of the thermoplastic substance to exude, as indicated at 19, so as to fill up the corner between the shoulder 11 and the face 15. The purpose of ironing the face 15 is to render it smooth and compact since it has usually become somewhat roughened by the passage of the knife over it. As a result there is produced a thin but strong blank which has a wide tapering margin of extreme thinness and at the same time is of considerable tensile strength when the blank is hot and limp. The finished marginal portion of the layer 5 will usually be of no more than some eight thousandths of an inch in thickness.

To promote adhesion between the layers one face at least of the two contacting faces of the fabrics which are to be impregnated is given a nap i. e. is fluffed up. Both these faces may be so treated so as to augment the absorbent capacity of the material while leaving it readily compressible when saturated and plastic to bring it to a definite gauge and later to obliterate the shoulder 11. The layer 3 may for these purposes have one or both of its faces raised but usually

the layer 5 will at most only have its inner face, if that, raised, as the desire will usually be to keep this layer as thin as possible.

If desired more than two layers can be used in this way in which case the matrix will be correspondingly stepped so as in the case of three layers (for example) to cause the knife to cut through one layer, travel some short distance between that layer and the middle one to split the layers apart and then plunge through the middle layer at some distance from the margin of the blank and finally travel out to the edge of the blank between the middle and remaining layer, splitting these apart in so doing.

The blank shown in Figs. 4 to 6 is composed of three layers of the impregnated fabric superposed and united after these layers have been cut from an impregnated sheet or sheets. The one outer layer 25 is of the full size of the blank, the other outer layer 27 is slightly smaller so that the layer 25 shall project a little beyond it round the front and side edges of the blank and is cut away at 29 to leave two thickened ends 31 corresponding to the ends 13 of Fig. 3, while the intermediate layer 33 is still smaller so that not only does the layer 27 project somewhat beyond it round the front and side edges of the blank but the rear edge of the layer 27, where it is cut away at 29, projects rearwardly beyond the rear edge of the layer 33 by a distance about equal to the distance by which the rear edge 35 of the layer 25 projects rearwardly beyond the rear edge of the layer 27 at the cut away portion of the latter. The distance between the rear edges of the layer 33 and 25 may equal some half inch or more, while the distance between corresponding other marginal portions of these layers may be some quarter of an inch. All three layers may be of the same character in every way or the intermediate layer may be made from 40 stouter fabric than the others. Conveniently those faces of the unsaturated fabric which are to be the inner faces of the outer layers may be fluffed or napped; and, if desired for the purpose of increasing the 45 absorbency and compressibility and otherwise modifying the properties of the middle layer as a vehicle for the thermoplastic material, the middle layer may be made from material that has been raised or napped on 50 one or both faces.

The cut layers may be superposed when cold and stiff and then be temporarily secured in relative position by applying a hot tool to the pile of layers at selected spots 55 where, consequently, they fuse together. The layers of the unit thus roughly formed and indicated in Fig. 5 may be finally welded together by heating it until all the layers have softened somewhat and then ironing it so that the layers are welded together,

and in addition so that, as previously described, the shoulder formed by the cut away portion 29 is obliterated and the rear edge of the layer 25, where it is exposed between the ends 13, is duly thinned down. 70 This action also is used to form in a similar way a bevelled edge round the front and side edges of the blank as indicated at the left hand end of Fig. 6.

The intermediate layer may comprise a 75 fabric which is thicker or of stiffer material or structure e. g. felt, or may be charged with more impregnant, as desired. While the impregnant for the outer layers is preferably so chosen as to give a flexible blank 80 and secure considerable adhesion between the layers, as already indicated, and the impregnant of the inner layer may be the same, the fact that the latter layer is encased between the two outer layers, united the one 85 to the other, admits of the use of a different impregnant for the inner layer—an impregnant which may be of a less adhesive nature and stronger and stiffer when cold so that an increased strength is given to the thick 90 portion of the blank without sacrificing marginal flexibility or introducing any undue tendency for the layers of the blank to come apart.

A convenient fabric for the layers 5 and 95 25 and for the layer 27 is a close woven cotton cloth of plain weave (i. e. with every thread passing over one cross thread and under the next) slightly fluffed or napped on the face that is to be the inner face of the 100 layer when it is in the stiffener. A convenient fabric for the layer 3 or the layer 33 is a cotton cloth the warp of which is of thread of much the same gauge as that of the cotton cloth just referred to while the 105 weft is of thread of about twice that diameter, and the weave is such the weft passes over two adjacent warp threads, then under the next two warp threads and once more over the next two warp threads giving in effect a plain weave with the warp made up of pairs of threads. This fabric may, for the blank shown in Figs. 1 to 3, be fluffed or napped on that face of it which will be the inner face in the blank, and for the blank 110 shown in Figs. 4 to 6 may be fluffed or raised on one face or both.

Having thus described my invention, what I claim as new and desire to secure by Letters Patent of the United States is:—

1. A toe stiffener for boots and shoes comprising a plurality of superposed layers of absorbent fabric impregnated with a thermoplastic material and securely united together, the middle portion of the upper of the layers being cut away at the rear end of the stiffener to expose an uncut portion of the lower layer whereby the rear margin of the stiffener has comparatively thick end portions and a thinner intermediate portion. 130

2. A toe stiffener for boots and shoes comprising a plurality of superposed layers of absorbent fabric impregnated with a thermoplastic material and securely united together, the rear margin of the stiffener having comparatively thick end portions formed of a plurality of layers and an intermediate thinner portion formed of a less number of layers.
3. A laminated thermoplastic toe stiffener for boots and shoes, the greater part of the rear margin of which consists of a projecting portion of a single lamina and the ends of which are reenforced by the presence of a portion of another lamina.
4. A toe stiffener for boots and shoes having a plurality of superposed layers of absorbent fabric impregnated with thermoplastic material and securely united together, said layers comprising outer layers of different sizes and an inner layer smaller than either of the outer layers and enclosed between them, said inner layer being charged with more impregnant substance per unit volume than are the outer layers, the arrangement being such that from its middle to the rear thereof the thickness of the stiffener is made up first of the thickness of all the layers, then of that of the outer layers, and then of that of one only of the outer layers.
5. The method of manufacturing a stiffener which comprises cutting from a piece of laminated sheet material impregnated with a thermoplastic substance a blank of the desired outline and thinning one margin of the blank by cutting away the margin of one of the laminae leaving uncut that of another.
6. The method of manufacturing a stiffener which comprises cutting from a piece of laminated sheet material impregnated with a thermoplastic substance a blank of the desired outline and thinning one margin of the blank by a cut which first severs one of the laminae a short distance from a margin of the blank and then passes between the severed lamina and the one adjacent to it to the extreme edge of the blank so as to remove from the blank the marginal portion of the severed lamina.
7. The method of manufacturing a stiffener which comprises cutting from a piece of laminated sheet material impregnated with a thermoplastic substance a blank of the desired outline, thinning one margin of the blank by cutting away the margin of one of the laminae and leaving uncut that of another, and obliterating the shoulder which results from the cut by application of heat and pressure.
8. The method of manufacturing a stiffener which comprises cutting from a piece of laminated sheet material impregnated with a thermoplastic substance a blank of the desired outline, thinning one margin of the blank by cutting away the margin of one of the laminae and leaving uncut that of another, and thinning the extreme margin of uncut lamina by application of heat and pressure.
9. A toe stiffener for boots and shoes comprising a plurality of superposed layers of absorbent fabric impregnated with a thermoplastic material and securely united together, a part of one of the outer layers projecting beyond the edge of an adjacent shorter layer to form a thin flexible rear margin of the stiffener, the rear edge of said shorter layer being compacted and beveled.

In testimony whereof I have signed my name to this specification.

FRED RICKS.
